(57) **CLAIM**

The ornamental design for a divot repair tool, as shown and described.

DESCRIPTION

FIG. 1 is a front view of the tool;

FIG. 2 is a side view of FIG. 1, the undisclosed opposite side being a identical;

FIG. 3 is a rear view of FIG. 1;

FIG. 4 is a top plan view of FIG. 1; and,

FIG. 5 is a bottom plan view of FIG. 1.

A handle for the tool is shown schematically in dashed line.
Its shape is arbitrary and forms no part of the invention.
